A. O. WICKERT, OF ST. LOUIS, MISSOURI

VENTILATOR

Application filed May 17, 1930. Serial No. 453,231.

My invention has relation to improvements in ventilators and it consists in the novel features of construction more fully set forth in the specification and pointed out in the claims.

The object of the present invention is to provide a ventilator for factories and similar types of buildings that is adapted to be mounted on the roof for the purpose of drawing from the building noxious or other disagreeable gases, for which purpose the ventilator comprises a short stack having a hood rotatably mounted thereover, within which are devices for accelerating the flow of the gases. A further object is to provide suitable lateral vents in the hood for the traverse of atmospheric currents which pick up the noxious gases passing through the ventilator and expedite their expulsion therefrom, thus increasing the velocity of the flow of these gases and increasing the efficiency of the ventilator. A further object is to provide a ventilator construction for accomplishing these results that is comparatively simple and inexpensive to build, and one possessing further and other advantages that will be better apparent from a detailed description of the invention in connection with the accompanying drawings, in which—

Fig. 1 is a front elevation of my improved ventilator; Fig. 2 is a rear elevation thereof; Fig. 3 is a vertical middle longitudinal section taken on the line 3—3 of Fig. 2; Fig. 4 is a top plan of the ventilator with parts broken away; and Fig. 5 is an enlarged sectional detail of the anti-friction bearing and support therefor by means of which the hood is rotatably mounted on the ventilator stack.

Referring to the drawings 1 represents a cylindrical stack having a rectangular base 2 within which lugs 3 are disposed at the corners for the purpose of securing the stack to the roof R of the building that is to be ventilated. Of course, the roof is provided with a vent opening O which allows the objectionable gases to escape therefrom into the stack

1. Immediately below the inwardly turned top edge 4 of the stack 1 is a cross member 5 and a second cross member 6 is spaced therefrom, for the support of a staff 7 which projects upwardly above the stack 1. The staff 50 in the present instance is hollow and has a plug 8 near its upper end between which and the inwardly turned edge 9 of the staff is loosely confined a ball 10, constituting together with edge 9 a bearing for rotatably 55 supporting the ventilator hood H.

It is in the hood H that the invention resides, the stack and its necessary elements being old in the art. The hood comprises a box-like structure having a skirt 11 from 60 which the rear wall 12 inclines upwardly as well as the triangular side walls 13, 13. The side walls 13, 13 extend forwardly beyond the skirt 11 and are connected thereto by a ledge or shelf 14 which forms the lower margin of the outlet opening of the hood. The top 15 of the hood is joined at its rear edge to the back 12, and inclines upwardly slightly from the horizontal to its forward edge 16 which is the top margin of the hood outlet. 65 The hood H has a second pair of side walls 17, 17 formed integrally with the top and connected at the bottom of their forward edges 17', 17' to the shelf 14, said forward edges forming the side margins of the outlet opening. It will be observed that the inner side walls 13, 13 converge slightly toward the top and rear, and outer side walls 17, 17 diverge slightly toward the rear of the hood 70 so that spaces s, s are formed between adjacent side walls 13 and 17 which spaces are open at the rear of the hood to permit the flow of atmospheric currents through the hood at the sides thereof.

A deflector D is secured inside the hood 75 (to the top 15 and back 12 thereof), said deflector having two deflecting surfaces 18, 19 on each side, joined along a medial plane to form parting edges 20, 21 for the rising gases. The rear deflecting surfaces 18, 18 80

are inclined upwardly and outwardly to divide the ascending gases into two streams and deflect these streams toward the inner side walls 13, 13 where they encounter the atmospheric currents passing from back to front of the hood through the spaces s, s. Because the front portion of the inner walls 13, 13 is cut away the divided gas currents will quickly enter the paths of the cross air currents.

10 A bearing plate 22 is secured within the hood H and takes the vertical thrust of the hood upon the ball 10, and a confining member 23 having a perforation 23' extends downwardly from said plate and receives the staff 7.

15 A vane 24 is mounted on the top 15 of the hood H toward the front thereof for the purpose of causing the hood to be rotated by the atmospheric air currents so that the outlet opening of the hood will always be away from the wind. Thus, the back of the hood will be turned into the wind so that atmospheric air currents will enter the spaces 20 s, s, heretofore referred to, (as shown in Fig. 4) and traverse the hood in paths adjacent to the side walls 13 and 17. The gases rising through the stack 1 will be deflected on encountering the parting edge 21 of the deflector D and will be turned by the deflecting surfaces 18, 18 toward the opposite sides of the hood. Since the forward portions of the side walls 13, 13 are cut away, these uprising gases will almost immediately encounter 25 the cross-atmospheric currents passing through the hood and will be expelled therefrom. Thus, it will be seen that I do not rely alone upon the injector action of the atmospheric currents through the hood but 30 provide means for actually projecting the vented gases into the atmospheric cross-currents which serve as the vehicle for removing them.

35 Having described my invention, I claim:
1. A ventilator comprising a stack, a hood rotatably mounted on said stack and adapted to receive the gases passing therefrom, said hood having an open front for the discharge of said gases and inner and outer side walls, said inner side walls being spaced from the outer walls and the hood open at the back between said spaced walls to permit the flow of atmospheric currents through said spaces, the inner side walls having free upper edges 40 inclining downwardly toward the gas outlet of the hood, and a deflector within the hood for diverting the uprising gases into the path of the cross-atmospheric currents.

45 2. A ventilator comprising a stack, a hood rotatably mounted on said stack and adapted to receive the gases passing therefrom, said hood having an open front for the discharge of said gases and inner and outer side walls, said inner side walls being spaced from the outer walls, and the hood open at the back

50 between said spaced walls to permit the flow of atmospheric currents through said spaces, the inner side walls converging upwardly and having free upper edges inclining downwardly toward the hood gas outlet, and a deflector 70 within the hood for diverting the uprising gases into the path of the cross-atmospheric currents.

55 In testimony whereof I hereunto affix my signature.
